UNITED STATES PATENT OFFICE.

JOHN FRANKLIN MACINDOE, OF PHILADELPHIA, PENNSYLVANIA, ASSIGNOR TO
HUTTON KENNEDY, OF PHILADELPHIA, PENNSYLVANIA.

GREASE-CUP.

1,159,517.

Specification of Letters Patent.

Patented Nov. 9, 1915.

Application filed November 21, 1914. Serial No. 873,288.

To all whom it may concern:

Be it known that I, JOHN FRANKLIN MACINDOE, a citizen of the United States, residing in Philadelphia, Pennsylvania, have invented certain Improvements in Grease-Cups, of which the following is a specification.

My invention relates to grease cups or lubricators from which the lubricant is ejected by means of pressure applied thereto, the pressure gradually lessening as the volume of lubricant diminishes, and the delivery passage being controlled by a valve movable with the pressure device so as to gradually increase the area of such passage as the pressure upon the lubricant decreases.

One object of my invention is to construct a simple and efficient lubricating device of this type, and a further object is to provide for effecting temporary increase in the volume of delivered lubricant whenever desired. These objects I attain in the manner hereinafter set forth, reference being had to the accompanying drawing, in which—

Figure 1 is a vertical sectional view of a fully charged lubricator constructed in accordance with my invention; Fig. 2 is a vertical sectional view of the same after most of the lubricant has been discharged therefrom; Fig. 3 is a horizontal section on the line $a-a$, Fig. 2; Fig. 4 is a view, partly in outside view and partly in horizontal section, on the line $b-b$, Fig. 2, and Fig. 5 is a vertical sectional view of a lubricator embodying a modification of my invention.

The body or cup 1 of the lubricator is closed at the top by a cap 2 and has at the bottom a nozzle 3 in which is formed the valve-controlled outlet passage 4 of the cup. Forming part of or secured to the nozzle structure 3 and extending up into the cup 1 is a tube 5, and to a transverse opening in the lower portion of this tube and corresponding openings in the nozzle structure 3 is adapted a transversely moving valve 6 notched or slotted for engagement with the lower end of a spring arm 7 which is suitably mounted at the upper end of the tube 5 and extends downwardly through the same for engagement with the valve 6, as shown in Figs. 1 and 2.

The tube 5 serves as a guide for the threaded stem 8 of a plunger 9 which fits

snugly to the inner wall of the cup 1, and is acted upon by a coiled spring 10 disposed between the back of the plunger 9 and the underside of the cap 2 and tending to constantly depress said plunger. The threaded plunger stem 8 passes freely through an opening in the cap 2 and is provided above said cap with a nut 11 which can be adjusted on said stem so that, by contact with the cap 2, it will limit, to any desired extent, the depression of the plunger 9 under the pressure of the spring 10.

The normal position of the spring arm 7 is that represented in Fig. 1 and tending to move the valve 6 so as to almost close the outlet passage 4, this position of the valve corresponding with the fully charged cup 70 in which the plunger 9 is raised to its highest point and the spring 10 is fully compressed, thus insuring maximum downward pressure upon the plunger to force the lubricant from the cup. As the volume of lubricant decreases, however, and the spring 10 expands, the pressure upon the plunger 9 gradually diminishes and in order to offset this diminution of pressure the valve 6 should be moved so as to gradually open the discharge passage 4 in proportion to such diminution of pressure upon the lubricant. In the cup shown in Figs. 1 and 2 this result is effected by mounting upon the upper end of the hollow stem 8 of the plunger a finger 12 which projects down inside said stem and into the tube 5, whereby, as the plunger descends, the finger 12 will also be caused to descend and will act upon the inner face of the spring arm 7 so as to move the same from the position shown in Fig. 1 to that shown in Fig. 2 and thereby cause corresponding movement of the valve 6 in order to gradually open the discharge passage 4 to accord with the decreasing pressure upon the lubricant and thus provide for a constant and uniform flow of lubricant to the bearing which is to be lubricated. It occasionally becomes necessary, however, to provide the bearing with an increased volume of lubricant for a short time, and, in order that this may be done, the valve 6 is susceptible of movement independently of the automatic adjusting means above described, so that whenever necessary the area 100 presented by the delivery passage for the

discharge of lubricant may be quickly increased. In the device shown in Figs. 1 and 2 this is effected by pressure upon the projecting end of the valve when the latter is 5 in the position shown in Fig. 1 so as to move said valve in the direction of the arrow shown in said figure, the valve, owing to the action of the spring arm 7, returning to its normal position again as soon as such pressure is removed.

While I prefer to use the transversely movable valve shown in Figs. 1 and 2 because of the compact and convenient construction of the lubricator thereby permitted, my invention is not limited to a valve of 15 this type, for instance in Fig. 5 I have illustrated a vertically disposed valve 13 contained within the plunger stem 8 and adapted to a seat in the forwardly projecting nozzle 3, this valve having, in its lower portion, one or more tapering ports 14 which gradually increase in area from the lower to the upper end, whereby, as the valve descends with the plunger, the area of the passage for 20 the lubricant will be gradually increased.

The upper end of the valve 13 is normally maintained in contact with the upper end of the plunger stem 8 by means of a spring 15 which surrounds the valve stem 16 and 30 bears upon a head 17 at the upper end thereof, the valve stem passing freely through an opening in the top of the plunger stem 8. Supposing, therefore, that the plunger is so disposed in the cup that the discharge of 35 lubricant from the latter is governed by the contracted port area of the valve, pressure upon the head 17 will serve to depress the valve 13 independently of the plunger and thereby quickly increase the area of the passage through which the lubricant is being 40 ejected, the spring 15, upon release of pressure from the head 17, immediately restoring the valve to its normal regulating position.

45 I claim:

1. In combination, a lubricating cup provided with an outlet, means for forcibly feeding the contents of the cup through said outlet and comprising a pressure device the 50 energy of which gradually decreases, and valve means controlling said outlet, said valve means being movable independently of said pressure device and being also automatically operable to increase the area of 55 the outlet in proportion to the decreasing energy of the pressure device.

2. In combination, a lubricating cup having an outlet, a spring actuated plunger in 60 said cup for forcibly discharging the lubricant through said outlet, a valve controlling the outlet, and movable independently of said plunger, and means for moving said valve simultaneously with the plunger.

3. In combination, a lubricating cup having an outlet, a spring actuated plunger in

said cup for forcibly discharging the lubricant through said outlet, a valve controlling the outlet and movable independently of the plunger, and means for effecting opening movement of the valve proportionate 70 to the movement of the plunger.

4. In combination, a lubricating cup having an outlet, a plunger for forcibly discharging the contents of the cup through said outlet, a valve controlling said outlet and movable independently of the plunger, and automatically operable means within the cup for causing opening movement of the valve in proportion to the lubricant discharging movement of the plunger. 75

5. In combination, a lubricating cup having an outlet, a valve controlling said outlet, a plunger for forcibly discharging the contents of the cup through said outlet, and automatically operable means within the cup 80 for causing opening movement of the valve in proportion to the lubricant discharging movement of the plunger, said means comprising a cam device having engaging members in operative connection respectively 85 with the valve and with the plunger.

6. In combination, a lubricating cup having an outlet, a valve controlling said outlet, a plunger for forcibly discharging the contents of the cup through said outlet, and automatically operable means within the cup 90 for causing opening movement of the valve in proportion to the lubricant discharging movement of the plunger, said means comprising a cam device connected to 95 said valve, and a cam actuating member movable with the plunger.

7. In combination, a lubricating cup having an outlet in its bottom, a valve mounted for opening and closing movement with respect to said outlet, a spring actuated plunger in the cup, a hollow stem connected with said plunger, an adjusting nut on said stem, a tubular member arranged in the stem and supported by the lower portion of the cup, 110 a cam device comprising a spring plate secured to said tubular member at one end and having interlocking connection at its other end with the valve, and an actuating member carried by the hollow stem and operating 115 in the tubular member to engage the cam device for automatically moving the valve as the plunger moves. 105

8. In combination, a lubricating cup provided with an outlet passage, means for 120 forcibly feeding the contents of the cup through said passage, and comprising a device the energy of which gradually decreases, a valve movable transversely across the outlet passage, and means whereby, as 125 the force of the feeding devices gradually decreases, the valve will be moved so as to gradually open said passage.

9. In combination, a lubricating cup provided with an outlet passage, means for 130

forcibly feeding the contents of the cup through said outlet passage and comprising a device the energy of which gradually decreases, an outlet-controlling valve movable to gradually increase its port area, yielding means for normally moving said valve into position corresponding to its minimum port area, and means whereby, as the energy of the feeding device gradually decreases, the 10 valve will be moved to gradually increase its port area.

10. In combination, a lubricating cup provided with an outlet passage, means for forcibly feeding the contents of the cup through said outlet passage and comprising-

ing a device the energy of which gradually decreases, an outlet-controlling valve, yielding means whereby said valve is moved to automatically increase the area of discharge as the force of the feeding device decreases, 20 and means whereby said valve can be moved independently of said feeding device to increase the area of discharge.

In testimony whereof, I have signed my name to this specification, in the presence of 25 two subscribing witnesses.

JOHN FRANKLIN MacINDOE.
